(57) **CLAIM**

I claim the ornamental design for a phone holder, as shown and described.

DESCRIPTION

FIG. 1 is a front view of the phone holder showing my new design.

FIG. 2 is a back view of the phone holder.

FIG. 3 is a left view of the phone holder.

FIG. 4 is a right view of the phone holder.

FIG. 5 is a top view of the phone holder.

FIG. 6 is a bottom view of the phone holder.

FIG. 7 is a perspective view of the phone holder.

FIG. 8 is another perspective view of the phone holder.

FIG. 9 is a perspective view of the phone holder shown in a configuration in which it may be used; and,

FIG. 10 is another perspective view of the phone holder shown in a configuration in which it may be used.
